UNITED STATES PATENT OFFICE.

HARRY M. HAUN, OF SAN BERNARDINO, CALIFORNIA, ASSIGNOR OF TWO-FIFTHS TO MARSHALL B. SARGENT, OF LOS ANGELES, CALIFORNIA, AND ONE-FIFTH TO EDGAR CORLETT, OF SAN FRANCISCO, CALIFORNIA.

RACK.

Application filed August 14, 1923. Serial No. 657,329.

To all whom it may concern:

Be it known that I, HARRY M. HAUN, a citizen of the United States, residing at San Bernardino, in the county of San Bernardino, and State of California, have invented new and useful Improvements in Racks, of which the following is a specification.

This invention contemplates an improvement over my co-pending application for 10 patent for racks, filed in the United States Patent Office March 24, 1923, Serial Number 627,875, and the invention has for an object the provision of a rack which presents while not in use a smooth flooring over 15 which trucking may be accomplished, as well as a rack which when in operation is self-adjustable, so as to accommodate for various unevennesses of the main floor to which the rack is secured. The rack is intended for use in box or refrigerator cars, 20 boats, or in any place where a rack may be essential.

With the above and other objects in view, the invention consists in the novel and useful provision, formation, construction, association and inter-relation of parts, members and features, all as shown in one embodiment in the accompanying drawing, described generally, and finally pointed out 30 in claims.

In the drawing:

Figure 1 is a fragmentary perspective view of a box car shown as incorporating the invention;

Figure 2 is a transverse sectional view of the box car showing certain of the racks in operative position and others in inoperative position, said view being taken on an enlarged scale;

Figure 3 is a fragmentary enlarged sectional view showing the rack members and the means for attaching certain units thereof together;

Figure 4 is a fragmentary perspective view of rack units and showing the operation of a hinge member between certain elements of such units; and

Figure 5 is a fragmentary cross sectional view on an enlarged scale, showing the method of associating rack units between the doorways of the car shown in Figure 1.

Corresponding parts in all the figures are designated by the same reference characters.

Referring with particularity to the drawing, the box car is designated by A and a unit rack section by B, each unit comprising two members as *a* and *b* hingedly associated by means *c*. Each member *a* and *b* has one edge thereof beveled, as shown at 1 and 2 respectively, and the means *c* permits the member *b*, which is movable relative to the member *a*, to swing upwardly upon the top surface of the member *a* and into the position as depicted by the dotted lines at 3 of Figure 3. It is intended that the member *a* of such unit rack section B should be fastened by any suitable means to the floor or other object upon which it is intended that the rack should be incorporated. In the showing of the figures each unit rack section B has its member *a* secured to the floor 4 of the box car A. Likewise in the showing the units B extend longitudinally of the car as shown at 5 with 75 certain of the sections B included between the doorway or doorways 6 and 7 of such car and the ends of such car, one of such ends being shown at 8, which is the bulk head of a refrigerator car. The rack on 80 the opposite side of the doorway, as shown at 9, is likewise extended from such doorway to the opposite end of such car, such opposite end not being shown. The structure between the doorways 6 and 7 comprises units differently associated with the flooring, and such units will be designated as B' to distinguish them from the ordinary sections shown at 5 and 9. Unit rack sections B are laid upon the floor in what 90 is termed an open position, such position being shown in Figure 3 in full lines and likewise in Figure 2 at 10, and they are laid in such a manner that they do not extend up to the side walls as 11 and 12 of the car A, this spacing being illustrated at 13 in Fig. 2. With the unit rack sections all open, as shown in Figure 2 at 10, the rack unit sections have their members *a* secured to the floor 4 longitudinally of the car. 95 When it is desired to use the rack sections the members *b* of said rack sections may be swung upon the top surface of the member *a*, as shown in Figure 2 at 14, whereupon it will be noted that channels 15 are formed 100 between the next adjacent unit rack section, as shown at 16. This permits an air space, as is obvious. Thus it is possible to truck

in through doorways and upon a smooth trucking surface such as shown at 10, and to place commodities such as shown at 17 upon the unit rack sections which have been 5 placed in position of service; that is to say, so that there are channels as 15 between such sections. A single member, 18, has a thickness corresponding to the thickness of the rack sections when in inoperative position and a width corresponding in height to the two members *a* and *b* when the member *b* is resting upon top of the member *a*. These members 18 are hingedly associated as at 19 with the flooring 4. It will be seen 15 in Figure 2 that the member 18 at 20 has been revolved against the side 12 so as to form a space 21 between itself and the next adjacent unit rack section *B* shown at 22. These members 18 likewise extend the 20 length of the unit rack sections *B* shown at 5 and 9 in Figure 1.

Considerable difficulty is experienced when for any reason the flooring 4 should be uneven or should contain objects thereupon 25 when the rack sections are in inoperative position. If the means *c* should be rigidly associated with the members *a* and *b* of the unit rack sections *B*, any object under the member *b* would cause the unit *b* to be 30 revolved slightly upwardly with the result that any load imposed on such member *b* by trucking thereover, would tend to strip the hinge connection between the members *a* and *b* loosening the hinge from such members. It is therefore an object of this 35 invention to provide a loose pin connection between the strap members joined to the sections *a* and *b* so that the member *b* will be self-adjustable to accommodate for any 40 unevenness of flooring or any objects upon the floor, without in any manner stripping the hinge connection between the members *a* and *b*. It is to be further noted that each 45 of the unit rack sections are independently operable and only the number desired for a given purpose need be used, and that the structure as shown does not take up space within a car other than would be ordinarily taken up by any rack within such car when 50 upon the flooring of such car. It is customary in certain known constructions to place the racks against the side walls of the car when in inoperative position, but such a structure of necessity uses up valuable 55 space in cars, whereas this structure does not. The means *c* for permitting loose or adjustable connection between the members of the unit rack sections includes a strap 23 for association with the member *b*, such strap being provided with a pin engaging loop 24, such strap being secured to the member *b*, by means of screws 25 or other 60 suitable securing elements, with a pin member 26 passed through the loop 24, and with 65 two legs of such pin member as 27 and 28

passed through sockets 29 in a strap member 30 secured to the member *a*. The ends of the legs 27-28 are inturned as shown at 31. This structure permits the member *b* to be lifted upwardly until the inturned 70 ends 31 engage the sockets 29 and stop upward movement. An idea of the adjustment allowed is shown in Figure 3 in which it will be noted that the member *b* is not resting upon the flooring 4, but is slightly 75 elevated therefrom without in any manner endangering the hinge connection. The strap 30 may be counter-sunk within the member *a*, as may likewise the strap 23 within the member *b*. The bevel edge 2 of 80 the member *b*, as shown in Figure 3 will cooperate with the bevel edge 1 of the of the next unit rack section, as will be readily seen in the showing of Figure 2. The member *b* may be formed with a finger-engaging 85 slot so that the same may be readily grasped to revolve the member *b* upon the member *a*. A member *d* approximately central of the car *A* extends the full length of such car, and said member has its edges beveled as 90 shown at 32 and 33, the said bevels corresponding to the beveled portion of the members *b*.

In the showing of Figure 5, which figure 95 illustrates the rack sections *B'*, it is to be noted that, as before, each unit rack section includes two members, as *a* and *b*, hingedly associated by the means *c*, but that the said members *a* are not secured to the flooring 4. Arms *e* and *f* are provided for the rack sections, and said arms are attachable to the member *a* of such units by suitable means such as shown at 36 in Fig. 5. The units *a* and *b* are channeled so that the arms may upon reception within such channels permit 100 the sections to lie flat upon the floor 4. The terminal portions of the arms *e* and *f*, as shown at 34 and 35 are bent and received in suitable grooves in the member *d*, and such terminal portions are provided with 105 pin-receiving loops so that the rack sections *B'* may either be received upon the floor or revolved upwardly into the position as illustrated at 38. The member *b* may be 110 revolved upon the member *a*, as before, and as shown in Figure 5 at 37. Thus it is possible to lock the two sections upon opposite sides of the member *d* in upright position and sweep débris from the floor or from between the channels between the rack 115 sections *B*, out the doorway. The units *a* and *b* of the rack sections *B* and *B'* are all provided with flutes or channels, as shown at 39 for the purpose of permitting circulation under the rack sections and likewise 120 acting as a protection against warp of the various sections.

It is obvious that various changes and 125 modifications may be made in practicing the invention, in departure from the par-

ticular showing of the drawing, without departing from the true spirit of the invention.

Having thus disclosed my invention, I claim and desire to secure by Letters Patent:

1. Improvements in racks, including a unit rack section formed in two parts, there being a loose hinge connection between such parts, whereby the two parts of such unit rack section may lie in the same plane to present a smooth working surface or one of such parts moved to a plane parallel to the plane of the first member.

2. Improvements in racks, including a unit rack section formed in two parts, there being a loose hinge connection between such parts; such parts being so formed as to cooperate when in one position to lie in the same plane.

3. Improvements in racks, including a unit rack section formed in two parts, there being a loose hinge connection between such parts; one edge of each part being beveled.

4. In car construction, a series of unit rack sections for placement in said car, each unit rack section comprising two members loosely connected together, whereby the two parts of such unit rack section may lie in the same plane to present a smooth working surface or one of such parts moved to a plane parallel to the plane of the first member.

5. In car construction, a series of unit rack sections for placement in said car, each unit rack section comprising two members loosely connected together; such car being formed with the usual flooring and one member of each unit rack section being secured to such flooring.

6. In car construction, a series of unit rack sections for placement in said car, each unit rack section comprising two members loosely connected together; such car being formed with the usual flooring and one member of each unit rack section being secured to such flooring; such unit rack sections cooperating to provide a smooth flooring when such unit rack sections are in one position.

7. In car construction, a series of unit rack sections for placement in said car, each unit rack section comprising two members loosely connected together; such car being formed with the usual flooring, and one member of each unit rack section being secured to such flooring; such unit rack sections cooperating to provide a smooth flooring when such unit rack sections are in one position; each unit rack section being independently operable.

8. Improvements in racks, including a series of unit rack sections, each section being formed in two parts, such unit rack sections when lying in one plane presenting a smooth working surface, and each unit rack section

being independently operable to move one of such parts to a plane parallel to the plane of the first part; an arm member, and one of such parts of each unit rack section being attached to such arm member.

9. Improvements in racks, including a series of unit rack sections, each section being formed in two parts, such unit rack sections when lying in one plane presenting a smooth working surface, and each unit rack section being independently operable to move one of such parts to a plane parallel to the plane of the first part; an arm member, and one of such parts of each unit rack section being attached to such arm member; in combination with the flooring of a car, there being means for pivotally associating the arm member with such flooring, and whereby the rack sections may either lie upon such flooring or be moved from such flooring upon movement of the arm member.

10. The combination with a car having the usual flooring, side wall members with doorways in said side wall members, of a series of cooperating unit rack sections for longitudinal placement upon the flooring of such car and extending from the doorway to an end of such car; each of such unit rack sections comprising two members loosely hinged together; such unit rack sections when lying in one plane presenting a smooth working surface, and each unit rack section being independently operable to move one of such members to a plane parallel to the plane of the first member.

11. The combination with a car having the usual flooring, side wall members with doorways in said side wall members, of a series of cooperating unit rack sections for longitudinal placement upon the flooring of such car and extending from the doorway to an end of such car; each of such unit rack sections comprising two members loosely hinged together; there being a member extending the full length of the car and located centrally of the car, and unit rack sections for placement between the doorways of such car.

12. The combination with a car having the usual flooring, side wall members with doorways in said side wall members, of a series of cooperating unit rack sections for longitudinal placement upon the flooring of such car and extending from the doorway to ends of such car; each of such unit rack sections comprising two members loosely hinged together; there being a member extending the full length of the car and located centrally of the car, and unit rack sections for placement between the doorways of such car; such latter unit rack sections being so formed as to permit the same to be lifted from the floor.

13. The combination with a car having the usual flooring, side wall members with

doorways in said side wall members, of a series of cooperating unit rack sections for longitudinal placement upon the flooring of such car and extending from the doorway to an end of such car; each of such unit rack sections comprising two members loosely hinged together; there being a member extending the full length of the car and located centrally of the car, and unit rack sections for placement between the doorways of such car; there being arm members pivotally associated with the member extending the length of the car and unit rack sections between the doorways of such car and attached to such arm members.

14. The combination with a car having the usual flooring, side wall members with doorways in said side wall members, of a series of cooperating unit rack sections for longitudinal placement upon the flooring of such car and extending from the doorway

to ends of such car; each of such unit rack sections comprising two members loosely hinged together; there being a member extending the full length of the car and located centrally of the car, and unit rack sections for placement between the doorways of such car; there being arm members pivotally associated with the member extending the length of the car and unit rack sections between the doorways of such car and attached to such arm members; such arm members permitting the unit rack sections to be lifted from the floor when the arm members are in one position.
